UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING MECHANISM FOR AUTOMATIC LOOMS.

Application filed May 8, 1926. Serial No. 107,770.

This invention relates to weft replenishing mechanism for a loom of the general type in which shifting shuttle boxes are provided at the magazine end of the loom.

5 It is the object of my invention to provide certain improvements in the general type of mechanism shown in my prior applications Serial No. 16,791 and No. 92,037.

10 Important features of my present invention relate to improved bobbin holding and presenting mechanism, to improved devices for holding and cutting the weft end attached to the transferred weft carrier, and to other arrangements and combinations of 15 parts which will be hereinafter described and more particularly pointed out in the appended claims.

A preferred form of the invention is shown in the drawings, in which

20 Fig. 1 is a partial right hand side elevation of a loom showing my improvements;

Fig. 2 is a front view of the end holder, looking in the direction of the arrow 2 in

Fig. 1;

25 Fig. 3 is a sectional elevation of the end holder, taken along the line 3—3 in Fig. 2;

Fig. 4 is a sectional plan view, taken substantially along the line 4—4 in Fig. 1; but with certain parts in a different position;

30 Fig. 5 is an enlarged detail sectional elevation, showing a thread cutting device and taken along the line 5—5 in Fig. 4;

Fig. 6 is a view similar to Fig. 5 but showing the parts in a different position;

35 Fig. 7 is a sectional end elevation, taken along the line 7—7 in Fig. 4; but with the carrier in a different position;

Fig. 8 is a sectional detail view, showing certain bobbin-holding devices;

40 Fig. 9 is a sectional elevation of a thread gripping device, taken along the line 9—9 in Fig. 4.

Fig. 10 is a plan view of the parts shown in Fig. 9;

45 Fig. 11 is a rear view of certain bobbin-holding devices; and

Fig. 12 is a detail sectional view, taken along the line 12—12 in Fig. 11.

Referring particularly to Figs. 1 and 4,

50 I have shown a portion of a loom frame 20, upon which is mounted a stationary weft carrier magazine M which is shown in the

drawings as being divided with three vertical bobbin-holding compartments.

A plurality of shuttle boxes 21 (Fig. 7) 55 are rotatably mounted at the right hand end of the lay 22 and these boxes are shifted angularly to bring any desired box to running position by means of a gear 23 rotatable with the boxes and positioned for engagement by rack bars 24 and 25, mounted at the upper end of an actuating rod 26. A second actuating rod 27 is effective to shift the rack bars transversely to cause one or the other rack bar to engage the gear 23. 60

By selectively shifting the rack bars 24 and 25, and selectively lifting or lowering the rod 26 and the rack bars connected thereto, the gear 23 and the associated shuttle boxes 21 may be moved angularly to bring 70 any selected box to running position.

A bobbin holder 30 (Fig. 1) is mounted at the upper end of an arm or rod 31 swinging about a pivot in the lower portion of the loom, preferably closely adjacent to the axis 75 about which the lay is moved.

A transerrer 33 is mounted for vertical sliding movement in a guideway 34 (Fig. 4) carried by the lay 22. A spring 36 acts to yieldingly raise the transerrer against a 80 stop screw 37, and an actuating arm 38 engages a roll 39 (Fig. 4) to give the transerrer an operative downward movement when weft replenishment is indicated.

All the parts thus far described are or may 85 be substantially as disclosed in my prior applications above noted, to which reference may be had for a more complete disclosure of the construction and operation thereof.

Bobbin holding mechanism.

I have provided certain improved devices for holding the bobbin during its rearward movement from the magazine and for presenting it in transfer position.

On indication of weft exhaustion, a bobbin B is released from one of the magazine compartments, as fully described in my prior applications, and drops onto a stationary plate 40 just as the bobbin holder 30 begins 100 its operative rearward movement.

The bobbin-holder 30 is substantially U-shaped in plan, as shown in Fig. 4, and is provided with a recess 41 for the butt of

the bobbin and with a smaller recess 42 for the tip of the bobbin. A yielding spring plate 43 (Fig. 8) engages the tip of the bobbin B adjacent the recess 42, said spring plate being rearwardly projected at its lower end portion to provide a yielding support for the bobbin.

As the bobbin is pushed rearward, it engages a yielding supporting and retarding device 45 (Fig. 7) having a concave lower end plate 46^a (Fig. 11) fitting the body of weft on the bobbin B. The device 45 is loosely pivoted on a rod 46, fixed at the rear of the magazine M, and is provided with a cross rod 47 resting upon rearwardly projecting curved supports 48 (Fig. 1). These supports are curved substantially in the arc of a circle struck from the center of the rock shaft of the lay, and cause the concave engaging plate 46 to travel rearward substantially in the arc of a circle corresponding to the path of the shuttle boxes.

To accommodate such movement, the upper ends of the supporting arms 49 of the device 45 are slotted or recessed as indicated at 50 in Figs. 1 and 12. Coil springs 51 engage projections on the arms 49 and force the device 45 yieldingly forward with sufficient pressure to prevent the bobbin from falling as it is moved rearward by the bobbin holder. The device 45 is limited in its rearward movement relative to the shuttle box by engagement with a stop arm 45^a (Fig. 4) on the lay end and which also acts to partially restore said device 45 to forward position, as the lay continues to move forward after transfer.

Thread holding device.

40 The rotary box construction introduces certain special requirements in the matter of disposing of the weft end attached to the transferred weft carrier. The end of the weft must obviously be firmly held both before and after the weft carrier is transferred, so that the weft will be drawn out of the shuttle and threaded in the shuttle eye as the shuttle is picked to the opposite side of the loom.

50 With the rotary boxes, however, it is desirable that the thread be severed at the time of transfer, so that the weft end may not be carried around the rotating box and obstruct the operation of the loom or become broken and be carried into the cloth.

Accordingly I have provided a special end holder and a special gripping and end-cutting device which I will now describe.

End holder.

60 My improved end holder comprises a casing 55, secured to the end of a depending wire or rod 56, fixed to the frame of the magazine M by a set screw 57 (Fig. 1). The casing 55 is provided with a series of vertical

slots 58, and a corresponding number of weights 59 are slidable vertically in the casing and are guided by studs 60 extending through the slots 58. Each weight 59 is provided with a pair of hooks 61 projecting upwardly therefrom and disposed at opposite sides of a cross rod 62.

The supporting rod 56 is provided with a rearwardly projecting arm 63 (Fig. 4) having a notch or a recess 64 (Fig. 1) to receive the weft ends leading from the bobbins or weft carriers in the magazine compartments. The weft end from each of the lowermost bobbins is led around the arm 63 and is disposed in the recess 64. The weft ends are then brought forward and are separately guided under the hooks 61 on the weights 59 and are then secured to an end-holding stud 65 (Figs. 2 and 3).

The object of the weights 59 is to take up 85 the slack thread and to keep the weft end under yielding tension during and following transfer, for a purpose to be described.

Thread gripping and cutting mechanism.

I have previously stated that it is desirable that the weft end for the newly transferred weft carrier shall be severed promptly after the transfer. To accomplish this purpose, I provide a thread gripping plate 70 (Figs. 4, 9 and 10) having a rear portion fixed to the top of the corresponding shuttle box and having its front portion yieldingly engaging the top of the box.

The front edge of the plate is turned 100 slightly upward to provide a wing, as indicated at 71 in Fig. 9, which causes the plate to be lifted and ride over a stud 72, fixed in the outer side of the bobbin holder 30 and movable rearwardly therewith. As the plate 105 is thus raised, the weft end is tensioned by its weight 59 and while thus under tension, it slips under the raised spring plate 70.

As the holder 30 reaches its extreme rearward position, the pin 72 passes beyond the 110 rear edge of the free end of the plate 70, as indicated in dotted lines in Fig. 10, and the plate snaps down, gripping the weft end thereunder.

I have also provided a thread cutter, comprising a lower jaw 75 (Figs. 5 and 6) mounted upon a bracket 76, secured to a frame member 77 carried by the lay 22. A second jaw 78 is pivoted at 79 on the bracket 76 on the fixed jaw and is held yieldingly 120 in raised or open position by a spring 80.

The transerrer 33 has a stud 81 (Fig. 4) projecting to the right over the movable cutter jaw 78. As the transerrer moves downward, the movable jaw is depressed to cut 125 the thread which has been drawn between the jaws from the end holder 63 to the spring plate 30, the relative position of the parts being clearly shown in Fig. 4.

The weft end is thus freed from the sta- 130

tionary end holder and is thereafter held by the spring plate 70, which is mounted upon and rotates with the associated shuttle box, so that there is no chance for the weft end 5 to obstruct the mechanism or to be broken thereby, during rotary movement of the boxes.

Having described the details of my invention, it will be seen that I have provided 10 very effective mechanism for holding the weft carrier during rearward movement and for presenting the weft carrier in transfer position. I have also provided effective means for holding the weft end during such 15 movement and for thereafter severing the weft end and holding the severed end on the shuttle box during subsequent operations of the loom.

In the weft-holding means, I have made 20 provision for yieldingly tensioning the weft end during the rearward presenting movement and during and after transfer. The weights 59 are preferably suspended by the weft ends somewhat below their topmost positions, so that they may be yieldingly raised to provide an increased length of weft if needed during presentation and transfer, while also effecting yielding tension thereon.

Having thus described my invention and 30 the advantages thereof, I do not wish to be limited to the details herein disclosed otherwise than as set forth in the claims, but what I do claim is:—

1. In a loom, a weft replenishing magazine, a weft end holder to which the weft ends from a plurality of weft carriers are secured, and means to separately apply yielding tension to each individual weft end secured to said end holder, at an intermediate 40 point between its weft carrier and said end holder and to maintain such tension during transfer.

2. In a loom, a weft replenishing magazine having a plurality of compartments, an end holder to which said weft ends from the carriers in different magazine compartments may be secured, and a plurality of separate tension devices, each engaging a weft end between one of said weft carriers and said 50 end holder and effective to yield and provide substantially uniform tension for its particular weft end during transfer of its weft carrier to a running shuttle.

3. In a loom, a weft replenishing magazine, a lay having a shuttle box, a shuttle therein, and means on said lay effective to grip and hold the weft end of a weft carrier transferred to said shuttle from said magazine, said holding means being operated to engage and securely grip said weft end before movement of said shuttle from its 60 shuttle box begins.

4. In a loom, a weft replenishing magazine, a lay having a shuttle box, a shuttle therein, means on said lay effective to grip

and hold the weft end of a weft carrier transferred to said shuttle from said magazine, said holding means being operated to engage and securely grip said weft end before movement of said shuttle from its shuttle box begins, and means to open said gripping device during presentation of the weft carrier to transfer position. 70

5. In a loom, a weft replenishing magazine, a lay, a shuttle box mounted at the magazine end of the lay, a weft carrier holding device movable rearward to present a weft carrier in transfer position, a weft end gripping device on said shuttle box, and means on said holding device effective to render said gripping device inoperative during a portion of the rearward movement of said holding device. 80

6. In a loom, a weft replenishing magazine, a lay, a shuttle box mounted at the magazine end of the lay, a weft carrier holding device movable rearward to present a weft carrier in transfer position, a weft end gripping device on said shuttle box, and means on said holding device effective to render said gripping device inoperative during a portion of the rearward movement of said holding device, said gripping device being thereafter released for effective operation as said holding device approaches its 95 extreme rearward position.

7. In a loom, a lay, a plurality of rotary shifting shuttle boxes mounted thereon, a weft replenishing magazine adjacent said boxes, a fixed end holder, a weft-gripping 100 spring plate on each shuttle box, and means to lift said plate as the fresh weft carrier is presented in transfer position, and to thereafter release said plate to grip and hold the weft end. 105

8. In a loom, a weft replenishing magazine, a lay having a shuttle box, a shuttle therein, means on said lay effective to grip and hold the weft end of a weft carrier transferred to said shuttle from said magazine, said holding means being operated to engage and securely grip said weft end before movement of said shuttle from its shuttle box begins, an end holder mounted separately from the lay and to which said weft end is preliminarily attached, and means on the lay to sever said weft end between said holding device and said end holder. 115

9. In a loom, a lay, a plurality of rotary shifting shuttle boxes mounted thereon, a weft replenishing magazine adjacent said boxes, a fixed end holder, means on each shuttle box to grip the weft of a newly inserted weft carrier, and means to sever said weft between said gripping means and said 125 end holder.

10. In a loom, a lay, a plurality of rotary shifting shuttle boxes mounted thereon, a weft replenishing magazine adjacent said boxes, a fixed end holder, means on each 130

shuttle box to grip the weft of a newly inserted weft carrier, and means to sever said weft between said gripping means and said end holder and prior to rotary shifting movement of said boxes.

11. In a loom, a lay, a transerrer, a weft end cutter mounted on said lay, and means on said transerrer engaging and actuating said cutter as a weft carrier is transferred.

12. In a loom, a lay, a shuttle box thereon, a weft replenishing magazine and a weft end holder both adjacent said shuttle box, and means to sever the thread between said end holder and a shuttle in said adjacent shuttle box and before movement of the shuttle begins.

13. In a loom, a lay, a shuttle box thereon, a weft replenishing magazine and a weft end holder both adjacent said shuttle box, 20 and means movable with said lay effective to sever the weft end between said adjacent shuttle box and said end holder.

14. In a loom, a lay, a shuttle box thereon, a weft replenishing magazine and a weft end holder both adjacent said shuttle box, 25 a thread cutter engaging the weft between a shuttle in said adjacent shuttle box and said end holder, and means to actuate said cutter.

15. In a loom, a lay, a shuttle box thereon, 30 a weft replenishing magazine and a weft end holder both adjacent said shuttle box, a thread cutter engaging the weft between a shuttle in said adjacent shuttle box and said end holder, and means to actuate said cutter, said latter means being operated only at the time of weft carrier transfer.

16. In a loom, a lay, a shuttle box thereon, a weft replenishing magazine and a weft end holder both adjacent said shuttle box, 40 a thread cutter engaging the weft between a shuttle in said adjacent shuttle box and said end holder, and means to actuate said cutter, said latter means being operative whenever a fresh weft carrier is inserted in 45 the running shuttle.

17. In a loom, an end holder, a lay having a lay end frame, a plurality of shuttle boxes movably mounted on said frame, a cutter blade secured to said lay end frame and extending forward above the active shuttle box, 50 a movable cutter blade co-operating with said first blade, and means to actuate said movable blade to sever the weft end between the shuttle box and the end holder.

18. In a loom, an end holder, a lay having a lay end frame, a plurality of shuttle boxes movably mounted on said frame, a cutter blade secured to said lay end frame and extending forward above the active shuttle box, 60 a pivoted cutter blade co-operating with said first blade, a transerrer, and means actuated by said transerrer effective to depress said pivoted cutter blade to sever a weft end between the shuttle box and the end holder.

19. In a loom, an end holder, a lay having a lay end frame, a plurality of shuttle boxes movably mounted on said frame, a cutter blade secured to said lay end frame and extending forward above the active shuttle box, 70 a pivoted cutter blade co-operating with said first blade, a transerrer mounted on the lay end frame and movable vertically to co-operate with the active shuttle, and means to depress said transerrer, said transerrer having a portion extending over 75 said pivoted blade and effective to give said blade a cutting movement as said transerrer descends.

20. In a loom, a weft replenishing magazine, a bobbin holding and presenting device having rearward portions engaging the bobbin, a retaining plate positioned for engagement by the rear portion of said bobbin, and means to yieldingly resist rearward movement of said bobbin and plate.

21. In a loom, a weft replenishing magazine, a bobbin holding and presenting device having rearward portions engaging the bobbin, a retaining plate positioned for engagement by the rear portion of said bobbin, 90 and means to yieldingly resist rearward movement of said plate, said bobbin being supported to prevent downward displacement by said retaining plate and said bobbin 95 holder only when in transfer position.

22. In a loom, a weft replenishing magazine, a bobbin holding and presenting device having rearward portions engaging the bobbin, a retaining plate positioned for engagement by the rear portion of said bobbin, 100 means to yieldingly resist rearward movement of said plate, said bobbin being supported to prevent downward displacement by said retaining plate and said bobbin 105 holder only when in transfer position, and a fixed supporting plate for said bobbin at the first portion of its rearward travel.

23. In a loom, a lay, a weft replenishing magazine, a bobbin holding and presenting device, a retaining plate positioned for engagement by the rear portion of said bobbin, means to yieldingly resist rearward movement of said plate, and means on the lay 110 effective to limit such rearward movement.

24. In a loom, a lay, a weft replenishing magazine, a bobbin holding and presenting device, a retaining plate positioned for engagement by the rear portion of said bobbin, means to yieldingly resist rearward movement of said plate, and means on the lay 115 effective to limit such rearward movement, and to give said plate an initial forward return movement.

25. In a loom, a lay, a weft replenishing magazine, a bobbin holding and presenting device, a retaining plate positioned for engagement by the rear portion of said bobbin, means to yieldingly resist rearward movement of said plate and means to guide said 120 125 130

plate vertically during such rearward movement, so that said plate and bobbin move substantially in the arc traversed by the lay.

26. In a loom, a lay, a weft replenishing magazine, a bobbin holding and presenting device, a retaining plate positioned for engagement by the rear portion of said bobbin, means to yieldingly resist rearward movement of said plate, said plate having a cross rod, and rearwardly extending guide rods on said magazine projecting beneath said cross rod and supporting and guiding said plate in its rearward movement.

10 vertical position of said plate as said plate moves rearward.

27. In a loom, a lay, a weft replenishing

magazine, a bobbin holding and presenting device, a retaining plate positioned for engagement by the rear portion of said bobbin, 15 means to yieldingly resist rearward movement of said plate, said plate having a cross rod, and rearwardly extending guide rods on said magazine projecting beneath said cross rod and supporting and guiding said plate in its rearward movement.

In testimony whereof I have hereunto affixed my signature.

ALBERT A. GORDON.
